UNITED STATES PATENT OFFICE.

JAMES K. SANDERS, OF CUBA, ILLINOIS.

WAGON-BOX RUB-IRON.

SPECIFICATION forming part of Letters Patent No. 241,824, dated May 24, 1881.

Application filed March 29, 1881. (No model.)

To all whom it may concern:

Be it known that I, JAMES K. SANDERS, of Cuba, in the county of Fulton, in the State of Illinois, have invented an Improvement in 5 Wagon-Box Rub-Irons; and I do hereby declare that the following is a full, clear, and exact description thereof, reference being had to the annexed drawings, making a part of this specification, in which like letters of reference 10 refer to like parts, and in which—

Figure 1 represents a view from the under side; Fig. 2, a side elevation; Fig. 3, a sectional elevation at x x ; Fig. 4, a perspective view; Fig. 5, a washer.

15 Rub-irons are attachments for the under edges of wagon-boxes, to prevent the forward wheels cutting into the wood when the team is turned around.

The object of this invention is to make a rub- 20 iron on which the wheel shall not rub at the same place all the time, and so cut a deep groove in one place while the rest of the rub-iron is comparatively whole. This result is accomplished by securing the rub-iron to the body 25 of the wagon by the one bolt, B, and in having this bolt pass through a long slot, A, running laterally in the body of the rub-iron C C.

30 D D is a rectangular washer, with a projection, E, fitting in the slot A, to prevent the said washer from turning around.

The head H of the rub-iron C C has the shoulder F, to butt against the edge of the wagon-box.

To further increase the wearing ability of this rub-iron, it is made double, and has a head, 35 H', with a shoulder, F', on the opposite side of the slot A A from the head H.

To adjust this rub-iron, unloose the nut of the bolt B, slide the iron along to a new position, and tighten up the bolt again. 40

When one head, H, is badly worn the nut and washer D can be removed, the rub-iron changed in position to bring the other head, H', in place, and the nut screwed on again.

What I claim as my invention, and for which I desire Letters Patent, is as follows, to wit:

1. In a wagon-box rub-iron, the rub-iron C C, head H, shoulder F, and slot A, in combination with the bolt B and washer D, with its projection E, substantially as and for the purpose specified. 45

2. In a wagon-box rub-iron, the rub-iron C C, head H, shoulder F, head H', shoulder F', and slot A, in combination with the bolt B and washer D, substantially as and for the purpose specified. 50 55

In testimony that I claim the foregoing invention I have hereunto set my hand this 19th day of March, 1881.

JAMES K. SANDERS.
